ADJUSTABLE PLASTER EAR

Merritt B. Austin, Jr., Winnetka, Ill.

Original application October 24, 1940, Serial No. 362,515. Divided and this application May 6, 1941, Serial No. 392,051

2 Claims. (Cl. 220—3.3)

The present invention relates to outlet boxes in electrical systems, and this application is a division of my application Serial No. 362,515, filed October 24, 1940.

More particularly, the present invention relates to an improved adjustable means for securing an outlet box to a wall structure.

Adjustable means are generally provided on outlet boxes for securing them to a wall in order to regulate the depth of the box with reference to the surface of wall coverings of various thicknesses. Owing to the relatively wide range of thickness of wall covering materials commonly used, such as plaster, plasterboard, and various types of nonplaster coverings, a relatively wide range of adjustment is required.

Heretofore, slotted fastening ears or brackets have been provided which were secured to the sides of an outlet box by means of screws extending through the slots. While reversal of the ears provided two ranges of adjustment, each range was limited by engagement of the screws with the end of the slot, and a relatively wide span remained in which the bracket could not be adjusted.

According to the present invention, an adjustable and reversible bracket or plaster ear is provided of relatively simple and convenient construction, which eliminates or materially lessens the span between the ranges of adjustment resulting upon reversing the bracket.

Moreover, according to the present invention, the bracket may be conveniently removed for reversing its position merely by loosening the fastening means even though the latter comprises a pair of aligned set screws engaging a single slot and even though the removal of the bracket from the box by sliding it outward toward the edge of the box is obstructed by a projection, such as an attaching ear having a cover plate.

Preferably, means is also provided to maintain the wall-engaging portion of the plaster ear parallel to the edge of the box, so that the box can be correctly positioned without special attention to the angular position of the bracket on the part of the workman.

Other features and advantages will hereinafter appear.

Referring to the accompanying drawing:

Fig. 1 is a side elevational view of an outlet box according to the present invention.

Fig. 2 is an end view of the outlet box showing an adjustable plaster ear in upright position.

Fig. 3 is similar to Fig. 2 but shows the plaster ear in inverted position.

Fig. 4 is a perspective view of the attaching ear.

Fig. 5 is a plan view of one end of the outlet box showing the plaster ear in upright position as in Fig. 2.

Referring to the drawing, the outlet box is constructed of sheet metal or some other suitable material and comprises a bottom wall 10, end walls 11 and side walls 12. The end walls 11 and bottom wall 10 are shown as integral, while the side walls are removable to permit a plurality of boxes to be used side by side as a gang box.

At the upper edges of the end walls 11, a pair of outwardly extending attaching ears 13 are provided for securing a cover plate to the box. Semipunched portions or knockouts 14 are provided in the side and end walls, said knockouts having slots 15 for the insertion of a screw driver or other tool whereby they may be pried out and removed to form apertures in the walls for receiving electrical conductors. A similar knockout 16 in the bottom wall 10 is adapted to form an aperture suitable for receiving electrical connections or for attaching the box to a bar hanger or other fixture supporting means.

The knockouts in the end walls are D-shaped with their straight edges coinciding with the bottom walls of the box, and suitable clamping means may be provided, as shown in my original application above referred to, for clamping cables extending through the resulting apertures. Extension of the D-shaped knockouts to the bottom wall of the box avoids the formation of a ridge which would tend to injure the insulation of the conductors when the clamping means is tightened.

According to the present invention, the adjustable means provided for securing the outlet box to a portion of a wall structure comprises a pair of ears or brackets, each having a flange 17 which extends outward at right angles from the end walls 11 of the box, and which is provided with means, such as holes 18, for securing the flange to a portion of a wall structure.

A bifurcated portion comprising two parallel tongues 19 forming a slot 20, is bent at right angles to flange 17 and is secured against the surface of the end wall 11 of the box by means of a pair of set screws 21 extending through the slot 20 and engaging the tongues 19 on either side thereof.

Preferably, the surface of the end wall 11 is indented to provide a pair of parallel shoulders 22 for engaging the parallel outer edges of

tongues 19 to retain the flange 17 parallel to the upper edge of the box.

Adjacent the junction of the flange 17 and tongues 19, the slot 20 is widened, as indicated at 23, sufficiently to accommodate the width of the attaching ear 13 on the upper edge of end wall 11, and the widened portion is extended into flange 17 forming an opening 24 to permit the bracket or plaster ear to be slid upward until flange 17 is flush with the upper edges of the box, the ear 13 fitting into the extended and widened portion 23 of the slot 20. The opening 24 which communicates with slot 20 is also wider than the heads of screws 21 so that it is possible for removal of the bracket to slide it downward past the set screws 21 merely by loosening the latter, but without the necessity of removing them.

In order to provide a range of adjustment for relatively thick wall coverings, the position of the bracket, as shown in Fig. 2, may be reversed in the manner shown in Fig. 3. By virtue of the widened opening 24 communicating with the slot 19, this reversal may be conveniently effected without removal of any other part of the box, and as a result of this reversibility, position of the flanges 17 may be adjusted within wide limits for securing the box at different levels with reference to the wall structure to which said flanges are attached. Thus the box may be mounted so that its edges are flush with a wide range of thicknesses of wall covering, such as wallboard, plaster, plasterboard, lath, metal lath, etc.

Variations and modifications may be made within the scope of this invention and portions of the improvements may be used without others.

I claim:

1. In an outlet box having an ear for attaching a cover plate projecting outward from a side wall of the box at right angles to the front edge of the box, adjustable means for securing the said box to a wall structure at varying depths, comprising an angular bracket consisting of a pair of flanges disposed in mutual angular relation, one of said flanges having means for securing it to a wall structure, and an opening therein extending to the junction of the flanges, said opening being of sufficient size to receive and straddle said projecting attaching ear; the other flange

having a relatively narrow slot extending from said opening to the end of the flange, normal to the junction of the flanges, said slot being widened adjacent the said opening to receive said attaching ear; and means carried by the said wall of the box below and in alignment with said ear extending through the slot to engage the edges thereof for fastening the bracket to said wall, said opening in the first-mentioned flange being adapted to slide over said slot-engaging means when the latter loosely engages the edges of the slot so that said bracket may be removed by sliding the same in either direction until the slot-engaging means is displaced from said slot through the open end thereof, or the communicating opening of the other flange.

2. In an outlet box having an ear for attaching a cover plate projecting outward from a side wall of the box at right angles to the front edge 20 of the box, adjustable means for securing the said box to a wall structure at varying depths, comprising an angular bracket consisting of a pair of flanges disposed in mutual angular relation, one of said flanges having means for securing it to a wall structure, and an opening therein extending to the junction of the flanges, said opening being of sufficient size to receive and straddle said projecting attaching ear; the other flange having a relatively narrow slot extending from said opening to the end of the flange, normal to the junction of the flanges, said slot being widened adjacent the said opening to receive said attaching ear; and means carried by the said wall of the box below and in alignment with said ear 30 extending through the slot to engage the edges thereof for fastening the bracket to said wall, said opening in the first-mentioned flange being adapted to slide over said slot-engaging means when the latter loosely engages the edges of the slot so that said bracket may be removed by sliding the same in either direction until the slot-engaging means is displaced from said slot through the open end thereof, or the communicating opening of the other flange, that portion 35 of the wall of the box engaged by said flange being depressed to the extent of the thickness of the flange and engaging the side edges of the flange to form a guideway therefor.
